(57) **CLAIM**

The ornamental design for digital video camera with built-in connector and lens, as shown and described.

DESCRIPTION

FIG. 1 is a front perspective view of a digital video camera with built-in connector and lens, a connector being in an extended position.

FIG. 2 is a rear perspective view thereof, with the connector being in an extended position.

FIG. 3 is a right side elevational view thereof, with the connector being in an extended position.

FIG. 4 is a left side elevational view thereof, with the connector being in an extended position.

FIG. 5 is a top plan view thereof, with the connector being in an extended position.

FIG. 6 is a front elevational view thereof, with the connector being in an extended position; and,

FIG. 7 is a rear elevational view thereof, with the connector being in an extended position.

The portions of broken lines in all figures illustrate contour of a camera and the transparent surface shading on the lens member represents the reflective nature of the lens. None of the broken lines form part of the claimed region.
